The present invention relates to improvements in or relating to wet-offset, variable-size rotary presses.

This invention is concerned more particularly with relatively simple means for positioning the various size cylinders.

To this end, the printing unit of a variable-size wet-offset rotary press comprises three superposed, rotatably driven cylinders, namely a top plate cylinder, an intermediate blanket or printing cylinder and a bottom impression cylinder, all these cylinders being tangent to each other during the operation of the press; the position of the top plate cylinder is fixed in relation to the frame structure of the unit, and the positions of the blanket and impression cylinders underlying the former may be adjusted vertically as a function of the format; this printing unit being characterized in that each one of said blanket and impression cylinders is rotatably mounted on a pair of supports mounted for vertical sliding adjustment on the two lateral frame structures of the printing unit, in that the movement of each support is controlled by means of a vertical screw, and that the pair of screws controlling the movements of the pair of supports of a same cylinder are rotatably and simultaneously driven from a common electromotor having two directions of rotation.

This invention is also concerned with other improvements relating to the rotary cylinder drive and also to the cylinder assembly and disassembly means, to the inking system, to the inking plate control device, to the inking system pick-up cylinder control device and to the sheet collecting device at the delivery end of the press. These improvements will become clearly apparent from the following description.

A typical form of embodiment of this invention will now be described by way of example with reference to the diagrammatic drawings attached hereto. In the drawings:

FIGURES 1a and 1b, assembled along the line a-b, constitute a simplified diagrammatic side-elevational view of the complete press;

FIGURE 2 is a side elevational view showing on a larger scale the wet-offset printing unit proper;

The generalities of the machine according to this invention will first be described with reference to FIGURE 1. As shown in this figure by way of example only the rotary press comprises:

(a) A roll carrier 1 of known type with automatic roll replacement. This apparatus comprises on its outlet side a device for brushing and vacuum-cleaning the web, and means for straightening the web issuing from the rolls;

(b) A paper feed device 2 with means for laying on the web laterally. This device, of the variable-size type, is also known per se;

(c) A number of variable-size wet-offset printing units 3 of which the various features will be described presently;

(d) An ink drying device 4 followed by a cooling system 5;

(e) A variable-size web tension device 6 of known type;

(f) A variable-size rotary cutting device 7;

(g) A sheet collector 8;

(h) A sheet retarding device 9;

(i) A clamp-chain sheet receiving device 10 of known type.

Now a variable-size wet offset printing unit will be described more in detail with specific reference to FIGURES 2, 17, 18 and 19 of the drawings.

The printing unit illustrated in elevational view in FIGURE 2 comprises a plate cylinder 11, a blanket cylinder 12 and an impression cylinder 13.

The cylinders 11, 12 and 13 are of the variable-size type in that their diameter varies as a function of the printing length contemplated.

The plate cylinder 11 has a fixed position. The positions of cylinders 12 and 13 (blanket and impression cylinders) are variable by vertical displacement.

In their operative positions they are normally in mutual contact. The web 15 from the preceding unit passes under a first guide roller 16, over the impression cylinder 13 and then under a second guide roller 17 from which it is directed towards the next unit.

It should be noted that according to a modified form of embodiment of this invention the web could extend horizontally between the blanket and impression cylinders

12, 13 without passing under the guide rollers 16 and 17.

The intermediate or blanket cylinder 12 is carried by a pair of supports 175, 176 sliding vertically without play on the pair of side frame structures 181, 182 of the printing unit, the bottom cylinder 13 being carried by another pair of sliding supports 177 and 178.

In the following disclosure the displacement and vertical setting or adjustment of the bottom impression cylinder 13 will be given in detail, it being understood however that this description applies as well to the cylinder 12 comprising similar mechanisms. In a specific form of embodiment, the sliding supports 177 and 178 are guided by dovetail-sectioned slideways 179 and 180 rigid with the lateral frame structures 181 and 182 of the unit. These slideways are of the automatic play take-up type.

The vertical displacement of supports 177 and 178 is produced by a pair of rotatably coupled vertical screws 183 and 184 either through a separate motor and reducing gear unit 185 for positioning and shifting the assembly, or through a handwheel 186 for the final parallel setting and pressure adjustment. The same applies to the vertical screws 197 and 198 controlling the movements of the sliding supports 175 and 176 of cylinder 12.

The aforesaid screws 183 and 184 are rotatably driven by a pair of helical gears 187 and 188 (see FIG. 19) driven in turn by worms 189 and 190 respectively. The worm 190 is keyed directly on a transverse shaft 191. The other worm 189 is mounted on this shaft not directly but through the medium of a sleeve 222, the handwheel 186 and a hub 192 slidably fitted on shaft 191 and rotatably connected thereto by means of a key 193. A knurled nut 194 screwed on the end of shaft 191, as shown, is operatively connected to said hub 192 through a radial pin 221 rigid with said hub 192 and engaging a circular groove 223 formed in said nut 194. Thus, it is adapted to cause the sliding movement of said hub 192 for rotatably driving in turn the handwheel 186 through the medium of a stud 195 parallel to the shaft axis. This stud is adapted to be inserted into any desired one of a plurality of positioning holes 196 drilled through the handwheel 186 at spaced intervals on a same circle.

The above-described arrangement permits of disconnecting the worm 189 from shaft 191 by simply unscrewing the knurled nut 194 so as to free the stud 195 from its positioning hole. Then, rotating the handwheel 186 will no more adjust the screw 183 or 197 so that the parallel relationship of the cylinders can be adjusted as desired. The stud 195 is subsequently introduced into the nearest hole 196, and the nut 194 is eventually tightened.

The manner in which the cylinders are relatively shifted will now be described.

Having carefully adjusted the pressure of cylinders 12 and 13, a quick relative shifting of these cylinders is produced when the press is stopped due to the provision of an automatic device energizing the motors 185 and 185A rotatably driving the screws 183, 184 and 197, 198 respectively, so as to lower firstly the bottom cylinder 13 and then the intermediate cylinder 12, the former being shifted twice as much as the latter.

The shifting motion will be described in detail only with reference to cylinder 12, since both cylinders 12 and 13 are supported and adjusted by the same means.

The motor and reducing-gear unit 185A comprises a friction clutch 199 which, through the medium of gears 200, 201 and 202, is adapted to drive the shaft 191 in the desired direction.

A stud 203 carried by a ring 204 has been positioned beforehand against a stop 205 carried by the frame structure 181 during the precision adjustment of the cylinder pressure. This ring 204 is positioned by means of a clamping collar 206 driving this ring through a pin 207. In the locked position the stud 203 is adapted to actuate a switch 208 for opening the motor energizing circuit (see FIGURES 17 and 19).

Stopping the press unit will start the motor 185A in the proper direction. This motor thus drives the shaft 191 and the stud 203 is rotated through substantially one revolution before re-engaging the stop 205. In this position corresponding to the cylinder shifting position it actuates the switch 209 for de-energizing the motor. The shock produced by the engagement of stud 203 with stop 205 is damped out by the provision of said friction clutch 199.

When the press is re-started the cylinders 12 and 13 are locked in position (with the assistance of a set of relays) by producing a sequence of steps constituting exactly the reverse of the shifting steps.

The web tension is kept to a constant value during the shifting of the counter-cylinder 13 due to the relative shifting of the guide rollers 16 and 17 responsive to conventional means (not shown) for keeping the web to a constant length.

Now the inking system will be described in detail with specific reference to FIGURES 2 to 5 of the drawings.

This inking system is of the conventional type comprising three inking plates and four dispensers with adjustable inkers. The ink-trough is of the flexible blade and reciprocating pick-up type.

The complete inking system is mounted on supports 24 slidably mounted on the lateral vertical frame structures 181, 182, the upward and downward movements of these supports being controlled by means of a pair of non-rotating screw rods 25 driven in the box 26 through a nut device by means of a worm and gear system driven in turn from an auxiliary motor.

The vertical adjustment is obtained by means of stops 27 bearing on the top of the box 26 and adjustable for each size, whereby the complete inking system may be shifted automatically when the press is stopped, and reset with the maximum precision, due to the provision of the adjustment stop, when re-starting the press.

As the dispenser adjustment device is of the conventional type, its description is not necessary for the understanding of this invention.

The ink-trough (see FIGURES 3, 4 and 5) is of the flexible blade type and its essential characteristic is that the blade is adjustable in either direction; in other words the blade may be moved at will towards or away from the ink-trough cylinder by means of control elements to be described hereinafter and which are positive in either case.

The ink-trough comprises essentially a support 28 carrying a pair of lateral flanges 28A, a flexible doctor blade 29 secured by rivets on a block 30 and an ink-trough cylinder 45. The operative end of this flexible blade has formed therein a number of small straps 31 solid with, and depending beneath the blade. Each strap 31 has associated therewith a lever 32 fulcrumed on a pin 33 carried by an adjustable support 34 slidably adjustable on the plate 34A. This lever 32 carries a pin 31A slidably engaging the strap 31 and is responsive to a pin 35 slidably engaging on the other hand a notch 36 formed in the lever 32. This pin 35 is carried by a support 37 secured to one end of a sliding rod 38. The opposite end of this sliding rod has screw-threaded portion 39 of very fine pitch. The movement of translation of this rod 38 is controlled by means of a nut 40 actuated by the operator through the medium of hand knobs 41 or 42 of different lengths to facilitate the identification of the alternations in the ink distribution.

The movement of translation of rod 38, which results from the rotation of a knob 41 or 42, will thus cause the lever 32 to pivot about the pin 33 and raise or lower the flexible blade 29 by means of the pin 31A engaging the strap 31.

To increase or reduce the elasticity of the doctor blade 29 it is only necessary slidably to move the support 34 in order to move the pin 31A towards or away from the end of blade 29. Under these conditions, the doctor blade

29 may be returned in either direction and therefore the ink distribution can be adjusted with a considerably higher degree of precision than with conventional blade devices.

A screw 38A carried by a small bracket 38B and provided with a lock nut 38C permits of adjusting the position of the ink-trough with respect to the cylinder by reacting against the member 38D secured to the distance-piece 38E.

The ink-trough is locked in the desired position by tightening wing-nuts 38F.

This assembly can be dismantled very rapidly by simply unscrewing the wing-nuts 38F and removing the ink-trough unit by causing same to slide along the member 38D.

Refitting this assembly is also extremely easy and the prior adjustment is preserved due to the provision of the set screw 38A.

Now reference will be made to FIGURES 6 and 7 to describe the ink-trough driving means.

The velocity of rotation of the ink-trough cylinder 45 is adjustable at will by means of the variable-speed gearing 43.

A clutch permitting of disconnecting the ink-trough cylinder 45 at will is also provided and consists of a sliding dog member or hub 44 movable along the shaft 45A of the ink-trough cylinder 45 and rotatably driving this shaft through key means. The counter-hub 46 is solid with a pinion 47 but the assembly 46-47 is not rotatably connected to the shaft 45A. The movement of rotation of pinion 47 is transmitted from the output shaft 48 of the variable-speed gearing 43 through the medium of other pinions 48 and 50.

The clutch may be actuated during the press operation by means of a two-armed lever 51 urged by a tension spring 51A and adapted to produce the sliding movement of the dog hub 44 by means of a cam face 52 formed on the end portion of a control lever 53.

Reference will now be made to FIGURES 8 and 9 to describe the means provided for driving the inking plates 165, 166 and 167 (FIGURE 2) to which a reciprocating motion is imparted.

A specific feature of this control arrangement resides on the one hand in the variation of the amplitude of this movement and on the other hand in the shifting movement produced at the end of the strokes.

In fact, it was observed that with the known systems equipping the greater part of printing presses, wherein the strokes terminate simultaneously in all inking plates, considerable and therefore detrimental vibration develops at high speeds.

The inking plate reciprocation is controlled by means of an eccentric 54. This eccentric rotatably drives a shaft 55 solid with a toothed wheel 56 meshing with another toothed wheel 57 rigid with the outer casing of a differential 58. The angular position of the fixed gear of differential 58 is adjustable by means of a handwheel 58A acting through the medium of a train of gears 58B, 58C and 58D. This differential 58 drives through a pinion 59 a toothed wheel 60 solid with a planet wheel 61 driving a sun wheel 62 solid with another eccentric 63. This eccentric 63 revolves at the same angular speed as the first eccentric 54, the transmission ratios of the differentials and of the train of gears being calculated accordingly.

Both eccentrics 63 and 54 will thus remain in the same angular relationship or timing during the movement of rotation, except is the adjustment of differential 58 is modified to vary the total eccentricity of the assembly and therefore the amplitude of the reciprocating movement which, on the other hand, may be reduced to zero in a specific relative position of the two eccentrics.

The assembly consisting of these two eccentrics 63 and 54 actuates a connecting rod 64 adapted, through a lever 65 fulcrumed at 66, to produce a lateral reciproca-

tion, according to a sinusoidal law, of the shaft 67 carrying an inking plate.

This device is repeated three times (one for each inking table) with a certain relative shift of the eccentrics, each group of eccentrics being shifted by 120° with respect to the preceding and next groups, so that the strokes are completed at different, alternate times for the purpose set forth hereinabove.

Now a specific form of embodiment of the control system of the pick-up cylinder 71 will be described with reference to FIGURES 10 and 11.

A specific setting of the time period during which the pick-up cylinder 71 contacts the ink-trough cylinder 45 has been devised by using a device adapted to be adjusted without stopping the press.

This device comprises essentially two cams 68 and 69 mounted on a common shaft 77 and adapted to be timed differently during the press operation; these cams are engaged by a common roller follower 70 carried by a lever 87 rigid with a transverse shaft 87A.

The relative shift of these cams 68 and 69 permits of adjusting the ink pick-up time by varying the angle corresponding to the top position of the pick-up cylinder 71. This angle may be reduced to a minimum approximating 0°.

The relative shifting of these cams is obtained by means of a differential 72 driven from a toothed wheel 73 meshing with a pinion 74 solid with the outer casing of differential 72 and driving in turn the cam 68 through a pair of gears 75 and 76.

The differential is so designed that the velocity of rotation of cam 68 is exactly the same as that of cam 69 carried by shaft 77.

The relative shifting of these cams 68 and 69 is obtained in the conventional manner during the press operation, by actuating the worm and gear device 78, 79 controlling the angular setting of the fixed gear of the differential.

A clutch device for disconnecting the pick-up cylinder 71 is also provided in the form of a shaft 80 carrying a pair of rings 81 and 82 formed each with a flat chord 83 and registering with the ends 86 of corresponding levers 84 and 85 in the "engaged" position obtained by actuating the lever 80A comprising detent-positioning means 80B becoming operative at the end of the stroke.

The pick-up cylinder 71 is carried by a pair of levers 71A and 71B fulcrumed on, but rotatably free from, shaft 87A.

Said levers 84 and 85 are connected to this shaft as well as the lever 87 carrying the roller follower 70 responsive to cams 68 and 69. These levers 84 and 85 carry a support 84A and 85B permitting of adjusting the parallelism and the pick-up member on the inking cylinder.

It may be noted that in FIGURE 10 the device controlling the pick-up cylinder 71 is shown in its inoperative position, that is, with the cylinder 71 in its lower position in which it cannot be actuated by the cams, the follower lever 87 being urged against said cams by a tension spring 71C.

Now the means for controlling the cylinder rotation and dismantling the cylinders will be described with reference mainly to FIGURES 12a and 12b.

Each press unit is driven from a main shaft 88 extending along and to the rear of the rotary press; this shaft is adapted to transmit the driving power through bevel gears 89, 90, 91 and 92 to a differential train of gears 93 driving in turn a vertical shaft 94.

This vertical shaft 94 is operatively connected to a second overlying vertical shaft 95 formed with splines, aligned with and coupled to the former by means of couplings 96, 97. Slidably mounted on this splined shaft 95 are bevel gears 98 and 99 rotatably driving the intermediate and bottom cylinders 12 and 13, respectively, as

already explained, on said sliding supports 175, 176, 177 and 178.

The bevel gears 98 and 99 drive through companion bevel gears 100 and 101 respectively a pair of shafts 102 and 103 driving in turn through tenon and groove couplings 104 and 105 the shafts of cylinders 12 and 13.

The bevel gears 98 and 99 are slidably mounted on the splined shaft 95 so that, without altering the cylinder drive, the shafts 102 and 103 can be moved up or down for adjustment according to the cylinder diameter, thus eliminating the size gears generally required in variable-size rotary presses.

The top cylinder 11 which, as already explained in the foregoing, is fixed in position, is driven through a similar device comprising bevel gears 106 and 107 driving a shaft 108 provided with a driving tenon 109 at its end.

The three driving tenons 104, 105 and 109 are provided for driving the cylinders 13, 12 and 11 but in such a manner as to permit an easy dismantling of these cylinders as well as the lateral adjustment, the latter being made with precision due to a known device disposed in front of the shaft of each cylinder.

The six cylinders are of the inset trunnion type. The device will be described in connection with only one of the cylinders, for example cylinder 13, as the other devices are similar thereto.

In their operative position the shaft trunnions 110 and 111 project from the cylinder 13. These trunnions have a tapered projecting portion of the Morse cone type, as shown at 150 and 151, which fit perfectly in female taper rings 152 and 153. These rings 152 and 153 are solid with a sleeve 161 rigid in turn with the cylinder 13.

The tapers 150 and 151 are adapted to slide within the rings 152 and 153 but cannot rotate in relation thereto due to the provision of sliding keys 162 and 163.

The tapers 150 and 151 are provided with cylindrical extensions 150A, 151A centered in the rings 154 and 155 so that the lateral sliding movements of tapers 150 and 151 keeps the cylinder 13 centered with respect to its axis in spite of these movements.

The rod 113 comprises a screw-threaded section 114 having a right-hand pitch and another screw-threaded section 115 having a left-hand pitch. The rod 113 is rotatably supported in rings 158 and 159 fitted in the sleeve 161 and is thus held against lateral or axial movement between these rings.

Now the dismantling operation will be described in connection with a single cylinder, for example cylinder 13. This dismantling operation is performed by causing the trunnions 110 and 111 to recede within the cylinder. This result is obtained by unscrewing a screw 112 normally intended for locking the cylinder-and-trunnion assembly on the front portion, and subsequently rotating in the proper direction the rod 113 having two screw-threaded portions 114, 115 having opposite pitches. By virtue of these opposite threads, the trunnions 110 and 111 gradually recede into the cylinder until the journals are retracted completely. Under these conditions, the cylinder 13 is supported by its journals 13A, 13B on rails 116, 117 previously moved to their "cylinder removal" position shown in chain-dotted lines in FIGURE 2, due to the provision of dovetail slidesways carried by said supports. Similar means for guiding the rails 116 and 117 are provided for the other cylinders 11 and 12, although they are not shown in FIGURE 12.

In FIGURE 2 it will be seen that the rails 116 and 117 are in a waiting position on the machine, and retracted inwards when the machine is in normal service condition.

The rails corresponding to cylinders 12 and 13 are mounted on the sliding supports 175, 176, 177 and 178 and constantly remain in the same vertical position with respect to the cylinder axis. When it is desired to replace the cylinder with another one, it is only necessary to pull the rails outwards, to the left, that is, to the position shown in chain-dotted lines in the drawing, and to roll

the cylinder or cylinders until they engage corresponding stops 116A and 117A provided to this end at the ends of rails 116 and 117.

The method of removing the cylinders will now be described with specific reference to FIGURES 13, 14 and 15.

The three cylinders 11, 12 and 13 can be removed simultaneously by using a device illustrated in FIGURES 13 and 14.

The cylinders 11, 12 and 13 are firstly placed on their rails in their removal position and then it is only necessary to bring in proper position a frame consisting of a pair of vertical uprights 118 and 119 constituting a kind of cradle and comprising three positions permitting of taking the cylinders by their journals 118A, 119A provided to this end, to lift same by means of a hoist 120, and eventually to transfer them to the desired position at the front or at the rear of the machine, after having returned the rails to their inoperative position.

As shown in FIGURE 15, the cylinders are removed by using preferably an overhead track 121 comprising points 121A leading to two side-tracks 121B and 121C, whereby the cylinders just removed from the press can be directed to one track, another set of cylinders, waiting on the other track, being transferred to the machine by following exactly the reverse procedure.

With this construction the printing or working size of the apparatus can be changed in the shortest time, this constituting a very important feature in the case of a variable-size rotary press.

Now reference will be made to FIGURE 16 to describe the sheet accumulator 321 and the sheet-retarding device 122 permitting of operating the press at very high speed while introducing the sheets into the chain receiving device 123 at a reasonable rate permitting an easy downward travel and stowing of the sheets.

The sheet accumulator consists essentially of a drum 124 revolving at a constant speed and having a developed peripheral length greater than the maximum length of the sheets delivered by the rotary cutter. This cylinder 40 is surrounded on the greater part of its periphery by a number of parallel very flexible belts 125 driven by contact at the same speed as said drum.

A series of small belts 126 are arranged under the lower portion of said drum and can be retracted downwards below the level of the sheet-supporting tables 128 and 129, due to the provision of a cam groove 127. These belts 126 are driven from, and have therefore the same peripheral speed as, the drum 124. The cam 127 controlling the movements of said small belts 126 revolves at a speed depending on the number of sheets accumulated around the cylinder.

In the specific case described hereinafter, the accumulation of five successive sheets is contemplated, but this number is obviously not compulsory. In this case, the 55 cam 127 performs one revolution every five revolutions of drum 124, and the cam contour is so designed that said belts 126 are retracted downwards during the time necessary for the passage of a sheet, and contact the drum surface during the time corresponding to the passage of four sheets. Therefore, these four sheets are wound sequentially around the drum by the action of these belts 125.

The belts 126 are cyclically retracted downwards by means of a device comprising a pair of co-acting levers 60 130, 131 and a link 132.

The belts 126 are tensioned with respect to the rotary cylinders 133 by levers 134 urged by tension springs 134A and fulcrumed on a bent lever 135 pivoted on a pin 136 rigid with the aforesaid lever 131.

The sheets fed by the input rollers 139 and 140 revolving at the same peripheral speed as the drum are sequentially wound on the drum 124 until (after the winding of the fourth sheet) the small belts 126 are retracted downwards and permit the delivery of the four sheets 75 with the fifth one aligning itself with the preceding four.

The sheets are then fed to the retarding device by discharge rollers 137 and 138 also revolving at the same peripheral velocity as said drum 124.

To operate properly, the retarding device 122 should be so positioned that the distance L corresponds substantially to the sheet length; to this end, the retarding device is adjustable as a unit in the longitudinal direction of the machine by means of a pinion and rack system 141, 142.

A first set of rollers 143, 144 carries along the sheet at the same linear speed as the preceding discharge rollers 137, 138. As contrasted thereto a second set of rollers 145, 146 feeds the sheets at a speed five times lower, but due to the provision of a cam 147 the cylinder 145 is in its upper position during the major fraction of the cycle and is lowered just as the rear edge of the sheets is released from the nip of the rollers 143 and 144 still pressed towards each other.

The low inertia of the sheets permits of changing their linear speed almost instantaneously and to introduce the five superposed sheets into the collector but at a speed five times lower than the normal feed rate of the machine.

The next pair of rollers 148 and 149 rotate at the same peripheral speed as rollers 145 and 146.

Now reference will be made to FIGURES 20, 21 and 22 to describe a modified form of embodiment of the mechanism controlling the vertical displacement of supports 175 and 176 of blanket cylinder 12, and supports 177 and 178 of impression cylinder 13.

The adjustment as a function of size is controlled by an electromotor 300 capable of revolving in either direction and adapted simultaneously to drive a pair of transverse shafts 250 and 251 through the medium of a train of gears designated as a whole by the reference numeral 301. These transverse shafts 250 and 251 are provided with a pair of corresponding worms at their ends, namely worms 252 and 252a solid with shaft 250 and worms 253 and 253a solid with shaft 251. These four worms 252, 252a, 253, 253a are in constant meshing engagement with gears such as 254 (FIGURE 22) keyed on the four vertical screws 198, 197, 184 and 183 respectively. Thus, when the motor 300 is energized, these four vertical screws 198, 197, 184 and 183 revolve in their nuts respectively rigid with supports 176, 175, 178 and 177 in order to move the cylinders 12 and 13 vertically.

When setting the size, the rotation of the four vertical screws is indicated by a counter 255 coupled with the transverse shaft 250 through a train of gears 255a. A vernier 256 is associated with this counter for directly presetting the selected size.

This adjustment, which is independent of the other mechanical and electrical means for positioning the cylinders 12 and 13, permits, when completed, of starting immediately the rotary press under the preselected new size conditions.

For applying and relieving the pressure to and from the cylinders, two motor and reduction-gearing units 302 and 303 having two directions of rotation are provided for driving respectively through friction couplings 257 and 258 and trains of gears 304 and 305 two transverse shafts 261 and 261a.

Since the mechanism and the principle of operation are the same for both cylinders 12 and 13, the following description will refer only to the mechanism for applying and relieving the pressure to and from the impression cylinder 13 under the control of said motor 303. The transverse connecting shaft 261a has its two ends rigid with a pair of opposite worms 262 and 262a (and on the other hand the transverse shaft 261 is rigid with worms 262b and 262c). As shown in FIGURE 22, the worm 262 is in constant meshing engagement with a gear 260 acting at the same time as a nut engaged by a hollow screw 259 mounted for rotation on the lower plain end portion 184a of the vertical screw 184, suitable bearings 306 and 307 being interposed therebetween.

Under these conditions, when the motor 303 rotatably

drives the shaft 261a, the rotation of the pair of worms 262 and 262a causes the simultaneous rotation of the pair of nut-forming gears 260. Since the screws 259 are held against rotation as a consequence of the irreversibility of the means controlling the parallelism and pressure parameters, the rotation of said nut-forming gears 260 will cause the vertical movement of the pair of hollow screws 259 and therefore of the two screws 183 and 184 of said supports 177 and 178 on which the impression cylinder 13 is mounted.

In FIGURES 21 and 22, it will be seen that the transverse connecting shaft 261 is also adapted rotatably to drive with one of its ends a pair of cams 263, 264 respectively through the medium of a transmission assembly 308 and 309. These cams 263 and 264 actuate respectively two electric switches 265 and 266 controlling the stoppage of the motor and reduction-gearing unit 302. A similar cam system is driven from the transverse shaft 261a and controls through a similar pair of switches the stoppage of the other motor and reduction-gearing unit 303.

When the blanket cylinder 12 is relieved under the control of motor 302 the relevant cam 263 stops the motor and reduction-gearing assembly 302 by actuating switch 265 substantially at the end of two complete revolutions of worms 262b and 262c.

When, on the other hand, the pressure is applied to this cylinder, the cam 263 stops likewise the same motor after two revolutions of the worms 262b and 262c in a direction opposite to the relieving direction. To determine with precision the final stoppage of said worms 262b and 262c, the transverse shaft 261 is rigid with a mechanical abutment member 267 co-acting with a fixed stop 268. The friction coupling 257 permits at the end of the rotational movement of damping out the shock between the abutment member 267 and its companion stop 268.

The operation is exactly the same in the case of the impression cylinder 13, when the pressure is applied and relieved to and from this cylinder.

The pair of cams 263 and 264 co-acting with the companion switches 265 and 266 afford two degrees of cylinder disengagement, namely a small shift under normal operating conditions and a large shift when it is desired to remove the cylinders.

On the other hand, it will be seen in FIGURE 21 that the transverse shaft 261a rotatably drives through the medium of a train of gears 269, 270a, 170b, 271, 272 and 273 compensation eccentrics 274 and 274a mounted on the shafts of counter cylinders 275 and 276 corresponding to the cylinders 16 and 17 of FIGURE 2. Thus, the length of the paper web is kept at a constant value.

The parallelism of the cylinder as adjusted at the manufacturer's workshop can subsequently be corrected.

This parallelism correction is performed by means of four handwheels (not shown) controlling the rotation of corresponding vertical shafts 277, 277a, 278 and 278a. Each one of these vertical shafts rotatably drives in turn a worm such as 280 shown in FIGURE 22. This worm 280 associated with the vertical screw 184 is rotatably driven from shaft 277 by means of a horizontal intermediate shaft 279. This worm 280 is in constant meshing engagement with a gear wheel 281 keyed on the lower portion of the aforesaid hollow screw 259 engaging the nut-forming wheel 260.

Thus, when the vertical shaft 277 is rotated by means of the handwheel associated therewith, the resulting rotation of worm 280 is transmitted through the keyed wheel 281 to the screw 259 in its nut 260. Thus, the hollow screw 259, the vertical screw 184 and the support 178 are displaced in a vertical direction.

The other three supports 177, 176 and 175 may thus be adjusted vertically by using similar mechanisms.

The vertical positioning of the cylinder supports is obtained by using graduated discs which are advantageous in that they afford a direct reading of the relative displace-

ments between the plate cylinder 11, the intermediate blanket cylinder 12 and the impression cylinder 13.

What I claim is:

1. Printing unit of a wet-offset, variables-size rotary press, comprising two vertical spaced frame structures, three horizontal superposed cylinders constituting a top plate cylinder, an intermediate blanket cylinder and a bottom impression cylinder, said cylinders being rotatably mounted between said vertical spaced frame structures and tangent to each other during the operation of the printing unit, the position of said top plate cylinder being fixed on said frame structures of the printing unit, a pair of first supports adapted to slide vertically on said vertical frame structures and to carry for rotation thereon said intermediate blanket cylinder, another pair of second supports mounted for vertical sliding movement on said vertical frame structures of the unit and rotatably supporting said bottom impression cylinder, whereby the positions of said blanket cylinder and said impression cylinder underlying the former are adjustable in a vertical direction as a function of size, a pair of first vertical screws controlling the vertical displacement of said first pair of supports respectively, a first electromotor operable in either direction for rotatably driving said first pair of vertical screws, a pair of second vertical screws controlling the vertical displacement of said second pair of supports respectively, and a second electromotor also operable in either direction for rotatably driving said second pair of vertical screws.

2. Printing unit as set forth in claim 1, wherein each lateral frame structure comprises a first, dovetail-sectioned slideway having mounted for vertical sliding movement thereon a first support and a second, dovetail-sectioned slideway slidably engaged by a second support.

3. Printing unit as set forth in claim 1, comprising, for rotatably driving each pair of vertical screws, a transverse shaft rotatably driven in turn from the corresponding electromotor, a first worm solid with said transverse shaft, a first helical gear rigid with one of said vertical screws and in constant meshing engagement with said first worm, a second helical gear rigid with said other vertical screw, a second worm in constant meshing engagement with said second helical gear, and means for mutually coupling said second worm and said transverse shaft while permitting of disconnecting said other vertical screw in relation to said transverse shaft.

4. Printing unit as set forth in claim 3, wherein said means for mutually coupling said second worm and said transverse shaft comprise a sleeve carried by said transverse shaft and solid with said second worm, an adjustment handwheel rotatably solid with said sleeve, a hub slidably mounted on said transverse shaft, a key rotatably connecting said hub to said transverse shaft, said hub being adapted to slide between a first axial position in which it is rotatably coupled with said adjustment handwheel so as to cause said second worm to rotate bodily with said transverse shaft, and a second axial position in which it is disconnected from said handwheel and permits of rotatably driving through said handwheel only said second worm for the final fine adjustment of the parallelism and pressure of said cylinder.

5. Printing unit as set forth in claim 4, comprising a knurled nut screwed to the end of said transverse shaft, said knurled nut being solid in translation but free in rotation with respect to said hub, a stud carried by said hub and a plurality of holes formed in said adjustment handwheel along a common circle and engageable by the stud carried by said hub, whereby said stud may releasably couple said hub and said adjustment handwheel in the desired relative position.

6. Printing unit as set forth in claim 3, comprising, for each pair of vertical screws, a friction coupling rotatably driven from the electromotor associated with the relevant pair of screws, a train of gears drivingly connecting said friction coupling to said transverse shaft, a ring locked

on said transverse shaft, a stud carried by said ring, a fixed stop member carried by a vertical frame structure and engageable by said studs during the pressure adjustment of said cylinders, first and second motor circuit breaking contacts mounted on said vertical frame structure on either side of said fixed stop member, whereby in each one of the two positions alternately engageable by said stud on either side of said stop member, which positions correspond respectively to the locking and unlocking of the cylinder pressure, said stud is adapted to actuate said first and second motor circuit breaking contacts respectively.

5 7. Printing unit as set forth in claim 1, comprising means for energizing, when the press is stopped, firstly 15 said second electromotor for rotating said second pair of vertical screws controlling said second supports of said bottom impression cylinder, and subsequently said first electromotor rotatably driving said first pair of vertical screws controlling the displacement of said first supports 20 of said intermediate blanket cylinder, said bottom impression cylinder being shifted twice as much as said intermediate blanket cylinder.

25 8. Printing unit as set forth in claim 1, comprising an inking system, a pair of third supports slidably mounted 30 on said vertical frame structures of the printing unit and having said inking system slidably mounted in turn thereon, a third electromotor controlling the vertical displacement of said pair of third supports and said inking system, and a stop member adjustable as a function of size for limiting the vertical displacement of said third supports.

35 9. Printing unit as set forth in claim 8, wherein said inking system comprises an ink trough of the flexible blade type and positive control means for adjusting the position of said flexible blade in either direction.

40 10. Printing unit as set forth in claim 9, comprising a 45 ink-trough cylinder, a fixed support on which said flexible blade is secured, a plurality of straps disposed at spaced intervals along said flexible blade, under the free end thereof adjacent to the ink-trough cylinder, a plurality of levers pivotally mounted on said flexible blade support and associated with said straps respectively, each lever carrying a pin engaging the associated strap, and means associated with said levers respectively for selectively pivoting same.

11. Printing press as set forth in claim 10, comprising 45 a support adjustable by sliding on the support of said flexible blade, a pin carried by said adjustable support and having pivotally mounted thereon a lever for positively controlling a strap in either direction, the adjustment of 50 said sliding support permitting of varying at will the elasticity of said flexible blade.

12. Printing unit as set forth in claim 11, comprising for each strap a rod slidably mounted on said fixed support and having a screw-threaded end, said rod being adapted to control the pivotal movements of the lever acting 55 on said strap in either direction, a nut screwed on the screw-threaded end of said sliding rod, and an adjustment knob solid with said nut.

13. Printing unit as set forth in claim 10, comprising a power shaft adapted rotatably to drive said ink trough 60 cylinder, a variable-speed gearing disposed between said power shaft and said ink trough cylinder for adjusting the velocity of rotation of said ink trough cylinder, and a dog-type clutch interposed between said power shaft and said ink trough cylinder.

65 14. Printing unit as set forth in claim 8, comprising at least one inking plate, a pivoting lever operatively connected to said inking plate, a link fulcrumed on said pivoting lever, and a rotatably driven variable-throw eccentric controlling said link to permit the lateral reciprocation of 70 said inking plate according to a sinusoidal law.

15. Printing unit as set forth in claim 14, comprising a first internal, rotatably driven eccentric, a first gear rotatably solid with said first internal eccentric, a differential comprising an outer casing, a fixed gear and an output gear, an adjustment handwheel for rotatably driving said

fixed gear of said differential, a second gear solid with said outer casing of said differential and meshing with said first gear, a second eccentric mounted externally to said first eccentric and a train of gears disposed between said differential output gear and said second eccentric, the transmission ratio provided by said differential and said connecting gears being so selected that said first and second eccentrics revolve at the same angular speed.

16. Printing press as set forth in claim 14, comprising three laterally reciprocated inking plates, each inking plate being responsive to a variable-throw eccentric, the three eccentrics being shifted angularly to each other by 120° in order to provide alternate stroke ends.

17. Printing press as set forth in claim 10, comprising a pick-up cylinder adapted to engage said ink-trough cylinder, a transverse shaft carried by the vertical frame structures of the unit and having said pick-up cylinder pivotally mounted thereon, a lever solid with said transverse shaft, a roller follower carried by said lever, a power shaft, a first cam rotatably driven from said power shaft and engageable by said roller follower, another rotary cam mounted in close vicinity of said first cam and also adapted to be engaged by said roller follower, a differential comprising an external casing, a fixed gear and an output shaft, a first train of gears coupling said differential output shaft to said second cam, a second train of gears coupling said power shaft to said outer casing of said differential, the transmission ratio between said two trains of gears being such that said two cams revolve at the same speed, and means for adjusting the relative angular setting of said fixed gear of said differential to permit the adjustment of the relative angular shift between said two cams and therefore varying the contact time between said pick-up cylinder and said ink-trough cylinder.

18. Printing unit as set forth in claim 1, comprising a vertical, rotatably driven splined shaft, a first bevel pinion secured to said splined shaft, a second bevel pinion in meshing engagement with said first bevel pinion, a first intermediate horizontal shaft carrying said second bevel pinion and rotatably driving said top plate cylinder, a third bevel pinion slidably mounted on said vertical splined shaft, a fourth bevel pinion meshing with said third bevel pinion, a second intermediate shaft carrying said fourth bevel pinion and rotatably driving said intermediate blanket cylinder, a fifth bevel pinion slidably mounted on said vertical splined shaft, a sixth bevel pinion meshing with said fifth pinion, a third intermediate shaft carrying said sixth bevel pinion and rotatably driving said bottom impression cylinder.

19. Printing unit as set forth in claim 18, comprising said first, second and third tenon-and-groove coupling devices disposed between respectively said first, second and third intermediate shafts and the shafts of said top plate cylinder, intermediate blanket cylinder and bottom impression cylinder.

20. Printing unit as set forth in claim 18, wherein each one of said cylinders carries a pair of opposite inset trunnions, of which one is coupled to the relevant intermediate shaft, said trunnions being journaled in the cylinder supports, said inset trunnions having tapered extensions inside said cylinder, a pair of internally tapered rings rigid with said cylinder and corresponding with precision to said tapered extensions of said trunnions, sliding keys for slidably mounting said tapered extensions of said inset trunnions in said internally tapered rings while locking same against rotation, an internal rod comprising two screw-threaded sections of opposite pitch which are screwed in said pair of extensions of said trunnions tapered respectively, one end of said rod being shaped to permit its rotation from external control means, and an internal support in which said rod is journaled, said internal support being locked against axial displacement.

21. Printing unit as set forth in claim 20, comprising for each cylinder a pair of rails mounted for horizontal

sliding movement on said cylinder supports, a pair of journals formed at the two ends of the relevant cylinder, and a pair of rails disposed beneath said journals respectively for supporting said cylinder when said trunnions are recessed into said cylinder.

5 22. Printing unit as set forth in claim 1, comprising an overhead track, a hoist suspended from said track, a movable frame structure supported by said hoist and comprising a pair of cradle-like vertical uprights each formed with bearing means whereby said three superposed cylinders can be lifted simultaneously by means of said hoist.

10 23. Printing unit as set forth in claim 22, comprising a main track section for said hoist, whereby said cylinders may be brought to a position in which they overlie said sliding rails in the supports of said cylinders, and switch means leading to a pair of side tracks.

15 24. A printing unit of a web-offset, variable-size rotary press, comprising two vertical spaced frame structures, three horizontal superposed cylinders constituting a top plate cylinder, an intermediate blanket cylinder and a bottom impression cylinder, said cylinders being rotatably mounted between said vertical spaced frame structures and tangent to each other during the operation of the printing unit, the position of said top plate cylinder being fixed on said frame structures of the printing unit, a pair of first supports adapted to slide vertically on said vertical frame structures and to carry for rotation thereon said intermediate blanket cylinder, another pair of second supports mounted for vertical sliding movement on said vertical frame structures of the unit and rotatably supporting said bottom and impression cylinders, whereby the positions of said blanket cylinder and said impression cylinder underlying the former are adjustable in the vertical direction as a function of size, a pair of first vertical screws controlling respectively the vertical displacement of said first pair of supports, a first electro-motor operable in either direction, first and second transverse shafts, a train of gears drivingly coupling said first and second transverse shafts to said first motor, a pair of first worms carried by each one of said first and second transverse shafts, a first gear wheel keyed on each one of said first and second vertical screws controlling the position of said first and second supports of said intermediate and bottom cylinders, said first four gear wheels meshing with the four first worms carried by said first and second transverse shafts, whereby the rotation of said first motor will produce the simultaneous vertical motion of said first and second supports for size adjustment purposes.

20 25. A printing unit as set forth in claim 24, comprising a counter driven from one of said first and second transverse shafts and a vernier associated with said counter for directly indicating the selected size.

25 26. A printing unit as set forth in claim 24, comprising, for applying and relieving the operating pressure to and from said cylinders, a second and a third electro-motors adapted to revolve in either direction, first and second friction coupling devices driven respectively from said second and third motors, third and fourth transverse shafts, second and third trains of gear wheels adapted respectively to couple said first and second friction coupling devices to said third and fourth transverse shafts, a pair of second worms carried by each one of said third and fourth transverse shafts, four hollow screws mounted for free rotation respectively on the lower ends of said four vertical screws and solid in translation with said four vertical screws, a second gear wheel constituting a nut in its inner portion and engaged on each one of said hollow screws, said four second worms carried by said third and fourth transverse shafts meshing respectively with said four hollow screws to permit the conversion of the rotary motion of said four second worms, caused by said second and third motors, into a vertical motion of said four vertical screws and therefore of said four ver-

tical screws controlling the position of said cylinder supports.

27. A printing unit as set forth in claim 26, comprising at least one first cam rotatably driven from said third vertical shaft, at least one second cam rotatably driven from said fourth transverse shaft, at least one first electrical switch responsive to said first cam and adapted to de-energize said second electromotor, at least one second electrical switch responsive to said second cam and adapted to de-energize said third electromotor, a mechanical abutment member carried by each one of said first and fourth transverse shafts, and a fixed stop associated with each one of said mechanical abutment members for limiting the permissible rotation of said third and fourth transverse shafts during the application of operating pressure to said cylinders.

28. A printing unit as set forth in claim 26, comprising a pair of counter-cylinders, a compensation eccentric co-axial with each one of said counter-cylinders, and a train of gears adapted to couple each one of said compensation eccentrics to one of said third and fourth transverse shafts.

29. A printing unit as set forth in claim 26 comprising, for adjusting the parallelism and pressure parameters, four third gear wheels keyed on the lower portions of
